United States Patent Office

Des. 203,059
Patented Nov. 30, 1965

203,059

NECKLACE OR SIMILAR ARTICLE

Louis P. Maroun, 1081 Elodie, Flint, Mich.

Filed June 22, 1964, Ser. No. 80,512

Term of patent 14 years

(Cl. D45—16)

Fig. 1

Fig. 2

FIGURE 1 is a front elevational view of the necklace or similar article and illustrating my new design;

The dominant characteristics of my design are shown in full lines in the drawing.

I claim:

The ornamental design for a necklace or similar article, substantially as shown and described.
